MAINE.

RAILWAY DUMP CAR.

Application filed November 1, 1923. Serial No. 672,058.

The present invention relates to railway dump cars.

The present invention has been illustrated and will be described in connection with a 5 railway dump car of the convertible type, that is, a type so constructed and arranged that said car may be used as a flat bottom car or as a dump car. According to the structure illustrated, dumping mechanism is 10 provided by means of which lading may be deposited outside of the tracks upon which the car is mounted and between tracks upon which the car is mounted. Operating mechanism is provided for controlling the dumping mechanism for the two classes of dumping referred to.

It is an object of the present invention to provide a construction of car and dumping mechanism which will be convenient for use 20 and sturdy in construction and which will not interfere with other parts of the car.

A further object of the present invention is to provide a construction of dumping mechanism which is readily applicable to 25 well known designs of dump car, and which will avoid certain interference with other parts of the car, which interference is now at times encountered in service.

The mechanism for dumping lading between the tracks upon which the car is 30 mounted involves, as a rule, a longitudinally extending rotatable shaft. As cars are at present commonly constructed, said longitudinally extending shaft has been located in

that when the car is round. 35 a position such that when the car is turning a sharp curve there is an interference between said shaft and the trucks of the car. It is an object of the present invention to provide a construction in which this interference is eliminated.

Further objects will appear as the description proceeds.

Referring to the drawings—

Figure 1 is a transverse sectional view of 45 a convertible car embodying the principles of the present invention;

Figure 2 is an end elevation of the car shown in Figure 1; and

Figure 3 represents a detail of construction.

The car chosen for illustration comprises the side walls 1, 1, and the end walls 2, 2. Stakes 3, 3 may be provided for strengthening the side walls 1, 1.

Arranged medially of the car in a longitudinal direction are the hopper forming walls 4 and 5, of which the wall 5 is provided with a swinging door 6 pivoted for swinging movement about the axis 7. A chain 8 is provided for controlling the swinging door 6, said chain 8 being mounted upon the longitudinally extending rotatable shaft 9. The mounting of said shaft will be referred to in detail hereinafter.

Mounted for swinging movement along axes placed near to the upper extremities of walls 4 and 5 are the swinging doors 10 and 11, which doors swing about the axes 12, 12. Said doors 10 and 11 are adapted selectively to assume inclined positions, as indicated by the door 10 in Figure 1, or horizontal positions as indicated by the door 11 in Figure 1. When said doors 10 and 11 are in their inclined positions, their swinging edges will abut against and be supported by the side 75 walls 1, 1 of the car and in these inclined positions said swinging doors 10 and 11 will form continuations of the hopper walls 4 and 5. Said swinging doors 10 and 11, when swung to their horizontal positions, 80 form part of the flat bottom of the car.

Pivoted near the axes 12, 12 are other swinging doors 13 and 14, which swing about the axes 15, 15. The doors 13 and 14 are adapted to assume horizontal positions 85 whereby they will complete the bottom wall of the car when the swinging doors 10 and 11 are in their horizontal positions. The swinging doors 13 and 14 are also adapted

to assume inclined positions as indicated by 90 the door 14 in Figure 1, whereby lading from the car may be directed outside of the tracks upon which the car is mounted. The doors 13 and 14 are controlled by the chains 16 and 17, respectively, which in turn are 95 controlled by the longitudinally extending rotatable shafts 18 and 19, respectively.

The numeral 20 indicates a cross-tie which underlies the doors 10 and 11 when said doors 10 and 11 are in their horizontal positions. It has been common practice in convertible car construction to mount the operating shaft 9 below the cross-tie 20, which arrangement has brought said operating shaft 9 to a level dangerously close to the 105 trucks of the car, which trucks are indicated by the wheels 21, 21 of said trucks. As a result of this arrangement interference has

UNITED STATES PATENT OFFICE.

WILLIAM J. HOSCEIT AND DAVID HINDAHL, OF CHICAGO, ILLINOIS, ASSIGNORS TO RODGER BALLAST CAR COMPANY, OF CHICAGO, ILLINOIS, A CORPORATION OF MAINE.

RAILWAY DUMP CAR.

Application filed November 1, 1923. Serial No. 672,058.

The present invention relates to railway dump cars.

The present invention has been illustrated and will be described in connection with a 5 railway dump car of the convertible type, that is, a type so constructed and arranged that said car may be used as a flat bottom car or as a dump car. According to the structure illustrated, dumping mechanism is 10 provided by means of which lading may be deposited outside of the tracks upon which the car is mounted and between tracks upon which the car is mounted. Operating mechanism is provided for controlling the dumping mechanism for the two classes of dumping referred to.

It is an object of the present invention to provide a construction of car and dumping mechanism which will be convenient for use 20 and sturdy in construction and which will not interfere with other parts of the car.

A further object of the present invention is to provide a construction of dumping mechanism which is readily applicable to 25 well known designs of dump car, and which will avoid certain interference with other parts of the car, which interference is now at times encountered in service.

The mechanism for dumping lading between the tracks upon which the car is 30 mounted involves, as a rule, a longitudinally extending rotatable shaft. As cars are at present commonly constructed, said longitudinally extending shaft has been located in 35 a position such that when the car is rounding a sharp curve there is an interference between said shaft and the trucks of the car. It is an object of the present invention to 40 provide a construction in which this interference is eliminated.

Further objects will appear as the description proceeds.

Referring to the drawings—

Figure 1 is a transverse sectional view of 45 a convertible car embodying the principles of the present invention;

Figure 2 is an end elevation of the car shown in Figure 1; and

Figure 3 represents a detail of construction.

The car chosen for illustration comprises the side walls 1, 1, and the end walls 2, 2. Stakes 3, 3 may be provided for strengthening the side walls 1, 1.

Arranged medially of the car in a longitudinal direction are the hopper forming walls 4 and 5, of which the wall 5 is provided with a swinging door 6 pivoted for swinging movement about the axis 7. A chain 8 is provided for controlling the 60 swinging door 6, said chain 8 being mounted upon the longitudinally extending rotatable shaft 9. The mounting of said shaft will be referred to in detail hereinafter.

Mounted for swinging movement along 65 axes placed near to the upper extremities of walls 4 and 5 are the swinging doors 10 and 11, which doors swing about the axes 12, 12. Said doors 10 and 11 are adapted selectively to assume inclined positions, as indicated by 70 the door 10 in Figure 1, or horizontal positions as indicated by the door 11 in Figure 1. When said doors 10 and 11 are in their inclined positions, their swinging edges will abut against and be supported by the side 75 walls 1, 1 of the car and in these inclined positions said swinging doors 10 and 11 will form continuations of the hopper walls 4 and 5. Said swinging doors 10 and 11, when swung to their horizontal positions, 80 form part of the flat bottom of the car.

Pivoted near the axes 12, 12 are other swinging doors 13 and 14, which swing about the axes 15, 15. The doors 13 and 14 are adapted to assume horizontal positions 85 whereby they will complete the bottom wall of the car when the swinging doors 10 and 11 are in their horizontal positions. The swinging doors 13 and 14 are also adapted to assume inclined positions as indicated by 90 the door 14 in Figure 1, whereby lading from the car may be directed outside of the tracks upon which the car is mounted. The doors 13 and 14 are controlled by the chains 16 and 17, respectively, which in turn are 95 controlled by the longitudinally extending rotatable shafts 18 and 19, respectively.

The numeral 20 indicates a cross-tie which underlies the doors 10 and 11 when said doors 10 and 11 are in their horizontal positions. It has been common practice in convertible car construction to mount the operating shaft 9 below the cross-tie 20, which arrangement has brought said operating shaft 9 to a level dangerously close to the 100 trucks of the car, which trucks are indicated by the wheels 21, 21 of said trucks. As a result of this arrangement interference has 105

been encountered between the longitudinally extending operating shaft 9 and the trucks when the car is rounding a relatively sharp curve. According to the present invention the operating shaft 9 is disposed in a position such that it extends through a hole in the cross-tie 20. This arrangement has the advantage that the operating shaft is located at a higher level than heretofore. Inasmuch as the operating shaft 9 preferably lies outside of the hopper wall 4, the raising of the level of said operating shaft 9 also involves the result that the operating shaft is moved further from the longitudinally vertical central plane of the car. This last mentioned feature has the advantage that the operating shaft 9 presents a greater clearance than has heretofore been the case with respect to the brakestaff 22 and the car coupling mechanism 23 which are located at the ends of the car.

The disposition of the operating shaft 9 through a hole in the cross-tie 20 has the further advantage that it affords an opportunity for an improved bearing means for said operating shaft 9. Referring to Figure 3, it will be noted that a bearing member 24 is supported by the cross-tie 20 by means of rivets 25, 25 or other preferred holding means. Inasmuch as the cross-tie 20 ordinarily takes the form of a channel and inasmuch as the hole for the longitudinally extending operating shaft 9 occurs in the web portion of said channel, no practical weakening effect is had upon the cross-tie. The advantage accrues that a simple, inexpensive and effective bearing is provided by said cross-tie for the longitudinally extending operating shaft 9.

According to the structure illustrated, the hopper wall 4 comprises the sheet steel portion 26 having the offset portion 27, which offset portion forms a shoulder for receiving the portion 28 of the hopper wall 4. The sheet steel portion 26 may be reinforced by the angle 29 and the longitudinally extending operating shaft 9 may be additionally supported by means of the strap 30 which is secured at one end to the sheet steel member 26 and at its other end to longitudinal sills 31, 31 forming part of the frame of the car. It will be noted that the longitudinal sills 31, 31 extend to the top of the cross tie 20, that is, the upper boundaries of said sills are in substantially the same plane as the upper boundary of said cross tie, and that the hopper wall 4 extends substantially to the upper boundary of its adjacent sill 31. By reason of the sheet steel construction and the angle 29 for stiffening same, a structure is provided which leaves plenty of room between the hopper wall 4 and the adjacent longitudinal sill 31 for mounting the operating shaft 9 in a position such that said shaft 9 extends through the web of the chan-

nel constituting the cross-tie 20, whereby said shaft 9 lies in a plane above the car wheels.

The functions of the apparatus above described will be clear without detailed description. Said functions may be briefly stated, however, as follows:

By reason of the change in the position of the operating shaft 9 from its former position below the cross-tie 20 to a position such that said shaft extends through said cross-tie, the result is attained that said operating shaft 9 is disposed in a position clear of the trucks so that there is no danger of interference with said trucks even when the car is rounding a sharp curve. Such an arrangement also provides an opportunity for a simple, inexpensive and effective bearing for the operating shaft 9, and also has the advantage that good clearance is provided at the ends of the car from the brakestaff and car coupling mechanism.

Although a preferred embodiment of the present invention has been described in detail, many modifications may be made without departing from the spirit of the invention. In this patent it is intended to cover all such modifications that fall within the scope of the appended claims.

What is claimed is:

1. In a dump car, in combination, a cross tie, longitudinal sills, walls between said sills forming a hopper, one of said walls including a sheet metal plate at the upper part of said wall, said sheet metal plate being offset at its lower portion to form a shoulder adapted to receive and support the remainder of said wall, said sheet metal plate extending to a region adjacent to the top of its corresponding longitudinal sill, and an operating shaft in the angle between said plate and said corresponding sill. 105
2. In a dump car, in combination, longitudinal sills, walls between said sills forming a hopper, one of said walls being located in angular relationship with one of said sills, a truck for supporting said car, an operating shaft extending longitudinally of said car for controlling said hopper, said operating shaft extending past said truck to the extremity of said car, said operating shaft being located in the angle between said one wall and its corresponding sill, the upper portion of said one wall comprising a sheet metal plate of less thickness than the remainder of said one wall for providing space for said shaft, whereby said shaft may be located out of interfering relationship with said truck. 115
3. In a dump car, in combination, a cross tie, longitudinal sills having their upper boundaries in substantially the same plane as the upper boundary of said cross tie, walls between said sills forming a hopper, one of said walls being located in angular relation- 125

ship with one of said sills and forming a re-entrant angle therewith, wheels for carrying said car, a brake staff and coupling mechanism, an operating shaft for said hopper located in said reentrant angle and extending through said cross tie in a position spaced from said brake staff and from said coupling mechanism, and a metallic strap fastened at its two ends to said mutually angularly disposed sill and wall for supporting said operating shaft.

4. In a dump car, in combination, longitudinal sills, walls between said sills forming a hopper, one of said walls being placed in angular relationship with its corresponding sill, a truck for supporting said car, an operating shaft in the angle between said one wall and its corresponding sill which shaft extends beyond said truck to the extremity of said car, the upper portion of said corresponding wall comprising a sheet metal member of less thickness than the remainder of said corresponding wall, whereby to permit the disposal of said operating shaft at a level above said truck, and a strap for supporting said shaft, said strap being secured to said plate and to said corresponding sill.

5. In a dump car, in combination, a cross tie, longitudinal sills having their upper

boundaries in substantially the same plane 30 as the upper boundary of said cross tie, walls between said sills forming a hopper, one of said walls being fixed relative to said sills and being placed in angular relationship with one of said sills to form a reentrant angle, said cross tie comprising a channel-shaped member, a bearing member carried by the web of said channel-shaped member, and an operating shaft mounted in said reentrant angle extending through the web of 40 said cross tie and having a bearing in said bearing member.

6. In a dump car, in combination, a cross tie, longitudinal sills having their upper boundaries in substantially the same plane 45 as the upper boundary of said cross tie, walls between said sills forming a hopper, one of said walls being placed in angular relationship with one of said sills to form a reentrant angle, an operating shaft in said reentrant angle and extending through said cross tie, and a metallic strap for supporting said shaft secured at its two ends to said mutually angularly disposed sill and wall.

Signed at Chicago, Illinois, this 27th day 55 of October, 1923.

WILLIAM J. HOSCEIT.

DAVID HINDAHL.
